UNITED STATES PATENT OFFICE

2,607,195

HYDRAULIC CONTROL FOR WINDOWS
AND THE LIKE

Annandale Cuthill and James C. McBroom, Los Angeles, Calif.; said McBroom assignor to said Cuthill

Application January 15, 1945, Serial No. 572,838

4 Claims. (Cl. 60—54.6)

1

Our invention relates to window constructions for buildings of all kinds.

This application is a continuation in part of our co-pending application for Window Construction, Serial No. 299,452, filed October 14, 1939, which terminated in Patent No. 2,371,154, issued March 13, 1945.

One of the principal objects of this invention is to provide a novel and relatively simple hydraulic means for opening, closing, or adjusting windows, whether of the conventional type, louver type, or the like.

Another important object of this invention is to provide novel and simple hydraulic means for controlling or operating, by a single means, a battery of windows, and also a novel and simple hydraulic means for remotely controlling or operating windows of various kinds.

An important object also of this invention is to provide a novelly constructed master control cylinder which may be operated rapidly to open windows, and which may be rapidly controlled for closing the windows, but in which the windows are closed gradually and by their own weight.

A further important object of this invention is to provide a novelly constructed operating cylinder for directly opening and closing the windows, but which is so constructed that direct operation or tampering with the windows, other than by means of the control cylinder, will not allow sufficient air to enter the line to permit operation of the operating cylinder.

A still further object of this invention is to provide operating cylinders which are so constructed that the windows may not be appreciably operated or tampered with without actuating or operating the operating cylinders.

With these and other objects in view, as will appear hereinafter, we have devised a window construction for buildings having certain novel features of combination arrangement of parts and portions, as will hereinafter be described in detail and particularly set forth in the appended claims, reference being had to the accompanying drawing and to the characters of reference thereon, which form a part of this application, in which:

Fig. 1 is a fragmentary elevation from the inside of a window, embodying our invention in one form;

Fig. 2 is a vertical section thereof taken through 2—2 of Fig. 1, with certain parts thereof broken away to facilitate the illustration;

Fig. 3 is a fragmentary sectional view in plan taken through 3—3 of Fig. 1;

2

Fig. 4 is an enlarged sectional view through the median portions of the master and one of the operating cylinders;

Fig. 5 is a transverse sectional view through one of the operating cylinders, taken on line 5—5 of Fig. 4; and

Fig. 6 is a diagrammatic view showing the control, by a master hydraulic cylinder, of the individual units for opening, closing, or adjusting separate windows.

Our hydraulic control, as shown in the drawing, is used in connection with a window structure and is housed in a window frame 1, which is constructed similarly to other windows for buildings. Within the frame is shown a louver-like construction consisting of panels 2, which are preferably long transparent plates of glass supported at the ends by brackets 3.

The lower edge of each bracket is secured to one end of the panel or plate 2. At one, that is, at the normally inner or room end of the bracket is a bearing pin 3^a, the same being shown as extending at right angles laterally or backwardly from the bracket.

The bearing pins 3^a extend backwardly into sockets positioned in the side of the window frame near the inner or room side thereof, and the panels or plates 2 are shiftable outwardly from substantially vertical depending positions.

If desired the bearing pivots of the plates may be any other suitable form of hinge.

The bracket extends upwardly from the plate 2 and is provided at its extended portion with a backwardly or laterally extending pivot pin or trunnion 4 whereby the bracket may be shifted about the pivotal axis of the bearing pin 3^a. The trunnions 4 extend backwardly from vertically extending plate portions 3^b of the brackets, intermediate the ends thereof.

At the opposite sides of the window frame are located operating members 5 which are shiftable vertically. These operating members are preferably flat strips and are positioned in conforming channels 1^c in the side elements of the window frame. These strips are provided with substantially transverse slots 5^a into which the trunnions 4 extend. Thus when the operating members 5 are raised or lowered, the trunnions 4 may move in the slots 5^a for tilting the plates about the pivotal axes without causing the operating members 5 to move laterally.

If desired the slots 5^a may be inclined outwardly and downwardly to facilitate the opening and closing of the plates.

The operating members are shown as slightly

recessed beyond the inner face of the side elements 14 of the window frame. Over the lower ends of these operating members are plates 6 for guarding and guiding the lower ends.

The panels or plates 2 of the window may be tilted outwardly about the pivots by a unitary slide 11 which is shown as vertically shiftable on the inside of one of the side elements of the window frame. This slide has an inwardly extending lug 11^a which is connected to the upper end of a plunger 12, which forms a part of and is reciprocally mounted in a master hydraulic cylinder 13 rigidly mounted in the window frame. At each side of the window and on the inside of the side elements of the frame is an operating hydraulic cylinder 14, which is located in a recess at the lower end of the side element of the window frame and immediately behind the operating member 5. Each cylinder is provided with a plunger 15 which is shown as directly connected to the inner side of the corresponding operating member 5. The lower end of the master hydraulic cylinder is connected by conduits 16 and 17, to the operating hydraulic cylinders 14 at the opposite sides of the window frame. Thus, when the slide 11 is shifted downwardly, fluid is forced into the cylinder 14, raising the operating members 5 and opening the windows, or as here shown, the window plates. A lock may be provided on the slide 11, or connected elements, to prevent the window plates from being opened, as will be described hereafter.

The operating members 5 are raised by fluid pressure in the hydraulic cylinders. To aid the downward shifting of these members, we have provided tension springs 7 to urge the members 5 downwardly when the pressure in the cylinders is released. In order to hold the slide in a certain position, after having been shifted, we have provided transversely serrated engaging or other friction surfaces 1^a and 11^b between the slide 11 and the portion of the frame 1 engaged by the slide.

At the head end, that is, at the lower end of the cylinder 13, is provided a compartment or distributing manifold 13^a which is connected directly to the conduits 16 and 17. The compartment 13^a is separated from the piston operating portion of the cylinder by a wall 13^b in which are provided a large orifice 13^c and smaller by-pass orifices 13^d. The port or orifice 13^c is of larger diameter and is normally covered by a ball valve 13^e which is forced against its seat or over the orifice by a spring 13^f.

As the operating member or slide 11 is forced downwardly, which forces the piston 12 downwardly into the cylinder 13, the ball valve 13^e is unseated, causing the operating fluid to be forced into the compartment 13^a through the port or orifices 13^c and 13^d. When the operating member or slide 11 is shifted to its closed position, the piston 12 may be raised, but the rate of movement of the piston is retarded, due to the valve or ball 13^e being seated, allowing the operating fluid to return to its main operating cylinder through the by-pass orifices 13^d at a slow rate.

If desired, a resilient or yieldable means may be provided in the rod 12^a connecting the piston 12 with the operating slide 11. Such yieldable connection may be provided by a spring 12^b provided between a shoulder 12^c and the end of a loop 12^d slidably embracing the rod 12^a at a spaced distance from the shoulder 12^c.

In order to prevent air from entering the fluid line when suddenly operating the slide 11 for

closing the windows, we have provided a piston means consisting of separate piston elements 15^a and 15^b which may engage each other end to end, or which may be separated, a slight separation being shown in Fig. 4. When desiring to open the window, the piston element 15^a is forced upwardly by the fluid pressure in the cylinder against the lower end of the element 15^b, forcing the same upwardly and the operating member 5 upwardly. The operating slide 11, however, may withdraw the element 15^a, allowing the element 15^b to follow more slowly for gradually closing the windows.

The element 15^b is split in an overlapping manner, in which the overlapped portions are arranged at a slight angle, providing cooperating wedge surfaces and enlarged or dovetail portions 15^c and 15^d. Thus, when it is attempted to open the window from the outside or from the window itself, the angular surface of the wedge or dovetail portion 15^c engages the adjacent wedge surface of the dovetail portion 15^d, causing a wedging of the piston element 15^b within the cylinder 14. In order to facilitate such wedging action, by causing the wedge portion 15^d to be forced against the wall of the cylinder 14, we have provided a compression spring 15^e which causes automatic separation of the dovetail portions. In this manner, the element 15^b of the piston means is prevented from being withdrawn to any appreciable extent from the cylinder 14.

Our operating means for simultaneously operating the panels or windows from both sides or edges is applicable for operating windows other than the type shown. Such operating means, as disclosed, is applicable also, as shown in Fig. 6, for operating simultaneously all the windows of a battery by a unitary means or by a master hydraulic cylinder, and also for operating the window or windows from remote positions.

Though we have shown and described a particular construction, combination, and arrangement of parts and portions, we do not wish to be limited to the same, but desire to include in the scope of our invention the construction, combination, and arrangement substantially as set forth in the appended claims.

We claim:

1. A hydraulic device for operating a movable window, comprising: a movable member connected to the window; a hydraulic cylinder having a piston means movable therein, said piston means including a first reciprocating piston and a second piston freely slidable in the cylinder; and fluid pressure means for forcing said second piston outwardly against said first piston, the first piston being movable independently of the second piston, the first piston comprising wedging elements positioned side by side in the cylinder, one element being directly connected to the movable member and adapted to wedge between the other wedge element and the adjacent wall of the cylinder when the first wedging element is withdrawn slightly from said cylinder by the movable member.

2. A hydraulic device for operating a movable window, comprising: a movable member connected to the window; a hydraulic cylinder having a piston means movable therein; said piston means including a first reciprocating piston and a second piston freely slidable in the cylinder; fluid pressure means for forcing said second piston outwardly against said first piston, the first piston being movable independently of the second piston, the first piston comprising wedging ele-

ments positioned side by side in the cylinder, one element being directly connected to the movable member and adapted to wedge between the other wedge element and the adjacent wall of the cylinder when the first wedging element is withdrawn slightly from said cylinder by the movable member; and a compression spring positioned between the adjacent sides of the wedging piston elements for normally separating the same so as to force the wedging elements against the wall of the cylinder.

3. A hydraulic device for operating a movable window, comprising: a movable member connected to the window; a hydraulic cylinder; a piston reciprocable in the cylinder, said piston comprising a pair of wedge elements positioned side by side within the cylinder, said wedge elements being located at diametrically opposite sides of the cylinder and being slidable longitudinally with respect to each other, one of said elements being connected to the movable member and adapted to be wedged by the other element against the wall of the cylinder when withdrawn slightly away from the last-named element by the movable member.

4. A hydraulic device for operating a movable window, comprising: a movable member connected to the window; a hydraulic cylinder; a piston reciprocable in the cylinder, said piston including a pair of wedge elements positioned side by side and at diametrically opposite sides within the cylinder and slidable longitudinally with respect to each other, said elements having engageable wedge faces inclined with respect to the axis of the cylinder, one of said wedge elements being connected to the movable member
